[57] **CLAIM**

The ornamental design for a sheet transfer machine for double-sided copying, substantially as shown and described.

DESCRIPTION

FIG. 1 is a front, top and left side perspective view of a sheet transfer machine for double-sided copying showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof; and

FIG. 7 is a bottom plan view thereof.

FIG. 1

FIG. 2

FIG. 3

FIG. 4

FIG. 5

FIG. 6

FIG. 7
